(57) **CLAIM**

The ornamental design for a combined screw, spike and bolt,
as shown, and described.

DESCRIPTION

FIG. 1 is a photograph showing a perspective view of a
combined screw, spike and bolt according to the invention;

FIG. 2 is a photograph showing a side view of a combined
screw, spike and bolt according to the invention;

FIG. 3 is a photograph showing a bottom side perspective
view of a combined screw, spike and bolt according to the
invention;

FIG. 4 is a photograph showing a bottom side perspective
view of a combined screw, spike and bolt according to the
invention;

FIG. 5 is a photograph showing a top side perspective view of
a combined screw, spike and bolt according to the invention;
and,

FIG. 6 is a photograph showing a top view of a combined
screw, spike and bolt according to the invention.
